SERVICE BREECHES

Filed Jan. 11, 1930

UNITED STATES PATENT OFFICE

JOSEPH A. LIEBERMAN, OF PHILADELPHIA, PENNSYLVANIA

SERVICE BREECHES

Application filed January 11, 1930. Serial No. 420,036.

My invention relates to a new and useful service breeches and it relates more particularly to a novel construction of the leg portion of breeches, whereby a good and comfortable fit is produced without the aid of any extraneous fastening, adjusting, or tightening devices.

It has been the practice, heretofore, to provide the legs of breeches with buttons, 10 buckles, laces, or the like for the purpose of adjusting the leg portion of the breeches to the size of the knee and calf portions of the leg of the person wearing the breeches. The amount of adjustment thus available was 15 necessarily limited, and was not always comfortable to the wearer. Furthermore, the fastening or tightening of buttons, buckles, or laces consumed considerable time and involved considerable trouble. A further 20 advantage is that the provision of buckles, laces, buttons, or other adjusting devices added considerably to the cost of production and called for replacement and repair.

It is therefore the object of my invention 25 to produce a novel leg construction for service breeches, which possesses a wide range of adjustment and accommodation without the aid of any extraneous fastening, adjusting, or tightening devices, thus eliminating 30 all effort and labor heretofore involved in the putting on and taking off of the breeches and reducing the cost of production.

To the above ends, my invention consists 35 in providing the knee and calf portions of the legs of breeches with elastic strips or bands which extend from the bottom edge of the breeches to a point above the knees and which are so arranged as to make the 40 legs of the breeches fit the legs of the wearer regardless of the particular shape or size of the legs of said wearer.

My invention further consists of various 45 other novel features of construction and advantage, all as hereinafter described and claimed.

For the purpose of illustrating my invention I have shown in the accompanying drawings two forms thereof which are at present preferred by me, since the same have been 50 found in practice to give satisfactory and

reliable results, although it is to be understood that the various instrumentalities of which my invention consists can be variously arranged and organized and that my invention is not limited to the precise arrangement 55 and organization of the instrumentalities as herein shown and described.

In the accompanying drawings:

Fig. 1 represents a front diagrammatic view of a novel service breeches construction 60 embodying my invention, shown in actual use.

Fig. 2 represents on an enlarged scale, a portion of the leg of a pair of breeches embodying my invention, showing details of 65 construction.

Figs. 3 and 4 represents on an enlarged scale plan views of the elastic members employed in a modified form of the invention.

Fig. 5 represents a section on line 5—5 of 70 Fig. 2.

Fig. 6 represents a section on line 6—6 of Fig. 2.

Fig. 7 represents a section on line 7—7 of Fig. 2. 75

Referring to the drawings, in which similar numerals of reference indicate corresponding parts, 1 designates a pair of breeches having the legs 2 which are composed of the front and rear sections 3 and 4, the outer edges 5 of which are inturned and joined by the seam 6. The front section 3 of the leg 2 of the breeches is provided with a reinforcing patch 7, the edges 8 of which are inturned and secured to edges of the 80 front section 3 by the seam or stitches 9. The reinforcing patch 7 covers the knee portion of the breeches which is exposed to excessive wear and when said patch is worn out it is removed by a simple ripping operation 85 and a new patch is sewed on, thus renovating the breeches and prolonging its life. The inside edges 10 and 11 of the front and rear sections 3 and 4 of the leg 2 are spaced by the elastic adjustment strip 12 of worsted or 90 knitted wool or any other elastic, expandible material, and which will next be described.

The strip 12, best seen in Fig. 2, is substantially rectangular at its lower portion with the opposite vertical edges thereof 100

joined to the edge 11 of the rear section 4 by the seam 15 and to the edge 10 of the front section 3 by the seam 16. The bottom edge 17 of the strip 12 is substantially flush with the bottom edge 18 of the leg 2 which is in-turned and secured by the seam 19.

The upper portion of the strip 12 is of a substantially triangular form with the hypotenuse of the triangle formed of the arc 10 of a circle so that a generally upwardly tapering effect is produced. The arcuate or tapering edge of the strip 12 meets the opposite vertical edge at the point 26, as will be understood from Fig. 2. 28 designates a reinforcing strip which is secured to the upper arcuate edge and lower corresponding vertical edge of the strip 12 and to the in-turned edge 11 of the rear section 4 by means of the seam or stitching 30.

If desired I may make the strip 12 of two pieces 13 and 14 (see Figs. 3 and 4) with the bottom edge 20 of the piece 13 stitched to the top edge 21 of the piece 14 thus producing the same effect and result as is obtained by the construction shown in Fig. 1, the united pieces 13 and 14 being secured in position in the identical manner above described. The preferred construction is shown in Figures 1 and 2.

By eliminating laces, buttons, buckles, or their equivalent, I not only produced a less expensive, more efficient, and less troublesome construction, but I have also produced a neat and attractive appearance not available when extraneous means for adjusting the width of the leg of the breeches are employed.

In practice I have found that buckles or buttons are very ineffective in adjusting the leg of a pair of ready-made breeches to the size of the leg of the wearer since it very frequently happens that the difference in the thickness of the calf and knee portions of the legs of persons who would otherwise take a given size of breeches is greater than the range of adjustment which buckles or buttons can afford. The use of lace, while it affords reasonably satisfactory adjustment, is undesirable since it adds considerably to the cost of manufacture and involves considerable time and effort in manipulation.

The elastic adjustment strip 12 is so knit or made as to be expansible or to give or stretch only laterally or transversely and not longitudinally, so that in the event of a person having a normal waist line and height, but an abnormally thin or thick calf or knee, the leg of the breeches will contract or expand, always to follow the exact contour or size of the leg, thereby producing a tight fit but not in any way interfering with the comfort of the wearer.

Since the thigh and seat portions of the breeches are always generously cut and proportioned, no adjustment of these parts is necessary, and I have therefore made my

novel adjustment strip of an upwardly tapering form, the widest portions of said strip coinciding with the calf and knee portions of the breeches where the greatest amount of adjustment is necessary. From the center of the knee upwardly the need for adjustment begins to decrease, so that a slight distance above the knee the adjustment strip tapers to and terminates at the point 26, as will be understood from the drawings.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having thus described my invention, what I claim as new, and desire to secure by Letters Patent, is:

1. An adjustable leg for service breeches comprising front and rear sections having their outer edges stitched together, a reinforcing knee patch stitched to said front section, and an elongated, transversely expansible, elastic strip having a front vertical edge stitched to the inner edge of said front section and having an opposite, generally vertical rear edge stitched to the inner edge of said rear section, the bottom edge of said strip being substantially flush with the bottom edge of said leg, said bottom edge of said leg and said elastic strip terminating in the region of the calf of the wearer, and the upper terminal of said strip being slightly above the knee of said leg.

2. An adjustable leg for service breeches comprising front and rear sections having their outer edges stitched together, a reinforcing knee patch stitched to said front section, an elongated, transversely expansible, elastic strip having a vertical front edge stitched to the inner edge of said front section, and having an opposite, generally vertical rear edge stitched to the inner edge of said rear section, the bottom edge of said strip being substantially flush with the bottom edge of said leg, said bottom edge of said leg and said elastic strip terminating in the region of the calf of the wearer, the upper terminal of said strip being slightly above the knee of said leg, and an inner reinforcing strip common to the vertical rear edge of said elastic strip and the contiguous inner edge of said rear section.

3. A service breeches including a pair of legs terminating in the region of the calf of the wearer, each of said legs having an elastic strip more distensible transversely than longitudinally, disposed in proximity to the inner leg seam thereof, at a point between the calf and tibia portions of the leg, each of said strips extending from the lower edge of

the leg to a point above the knee of the wearer, the front longitudinal edge of each of said elastic strips being generally straight and the opposite rear longitudinal edge of each of said elastic strips converging upwardly to its junction with said generally straight front edge at a point above the knee of the wearer.
